[57] CLAIM

The ornamental design for a wheel trim, as shown and described.

DESCRIPTION

FIG. 1 is a front elevational view of a wheel trim showing my new design;

FIG. 2 is a rear elevational view thereof;

FIG. 3 is a right side elevational view thereof;

FIG. 4 is an enlarged sectional view taken along line IV—IV of FIG. 1;

FIG. 5 is a front perspective view thereof; and,

FIG. 6 is a rear perspective view thereof with inflation tubes fitted thereto, it being understood that the inflation tubes are omitted in FIGS. 2, 3 and 5 for clarity of illustration.
